UNITED STATES PATENT OFFICE.

FRIEDRICH MORITZ ALEXANDER NEUBERT, OF DRESDEN, GERMANY.

DESIGN FOR AN AUTOMATIC SALESMAN FOR CIGARETTES.

50,355.

Specification for Design.

Patented Feb. 20, 1917.

Application filed May 12, 1916. Serial No. 97,204. Term of patent 14 years.

To all whom it may concern:

Be it known that I, FRIEDRICH MORITZ ALEXANDER NEUBERT, a citizen of the Empire of Germany, residing in Dresden, in the Kingdom of Saxony, Germany, have invented a new, original, and ornamental Design for an Automatic Salesman for Cigarettes, of which the following is a specification, reference being had to the accompanying drawing, forming part thereof.

The design is shown in the accompanying

drawing, in which Figure 1 is a front view of an automatic salesman for cigarettes embodying the design and Fig. 2 is a view from one side thereof.

I claim:

The ornamental design for an automatic salesman for cigarettes as shown.

FRIEDRICH MORITZ ALEXANDER NEUBERT.

Witnesses:

RICHARD IFFERTE,
PAUL LIENEUNRUN.
